GARMENT ATTACHMENT

Filed Sept. 12, 1930

UNITED STATES PATENT OFFICE

NATHANIEL MORIN, OF MONTREAL, QUEBEC, CANADA

GARMENT ATTACHMENT

Application filed September 12, 1930. Serial No. 481,558.

The present invention relates to improvements in garment attachments and has particular reference to a foldable device adapted to be connected with the waistband portion of a garment to facilitate folding of the garment in accordance with the crease or folds thereof.

An important object of the invention is the provision of a foldable garment attachment adapted to be connected in association with the waistband portion of a garment to permit convenient folding of the garment in registration with the folds or creases therein.

A further object of the invention is the provision of a hingedly foldable device adapted to be connected in concealed position with trousers or similar garments and arranged so that when the waist portion of the garment is folded the hinged sections will correspond with the creases of the garment so that the garment is thus folded in proper crease preserving arrangement.

Another object of the invention is the provision of a device of the above character which is simple and durable in construction and which can be readily mounted in connection with a garment.

Other objects and advantages of the invention will become apparent as the description progresses.

In the accompanying drawings forming a part of this specification and in which like reference characters are employed to designate corresponding parts throughout the same:

Figure 1 is a perspective view of a front foldable attachment shown in extended open position,

Figure 2 is a perspective view of a rear attachment,

Figure 3 is a side elevational view of a pair of trousers showing the attachments connected in proper position thereon,

Figure 4 is an enlarged horizontal section taken on the line 4-4 of Figure 3.

Figure 5 is an enlarged fragmentary horizontal section showing the disposition of the rear attachment when the garment is disposed in proper position on the person, and

Figure 6 is an enlarged vertical section taken on the line 6-6 of Figure 3.

Referring to the drawings, wherein for the purpose of illustration is shown a preferred embodiment of the invention, the numeral 10 generally designates a garment in the form of a pair of trousers having attached, in the waistband portion, a pair of front foldable stiffener attachments 11 and a rear stiffener attachment 12. The attachments 11 and 12 are preferably disposed between the interior lining and the outer body material of the trousers so as to be entirely concealed.

Each of the two front attachments embodies a relatively long section 15 and a complementary shorter section 16. At the adjacent end edges, the sections 15 and 16 are formed with rolled interfitting hinge sleeves united by a pintle 17 to form a hinge connection therebetween. Furthermore, each of the sections 15 and 16 is formed with spaced apertures 18 formed to accommodate therethrough the shanks of buttons 19.

The rear attachment 12 embodies a pair of substantially identical complementary sections 20 provided with spaced apertures 21 and united by a hinge construction 22 formed in accordance with the hinge structure described in the foregoing for the connection of the sections of the front attachment.

The sections 15, 16 and 20 of the forward and rear garment attachments are preferably composed of flat elongated metallic strips constructed so as to be pliable to permit bending in conformity with the waistline contour of the wearer and convenient straightening when the garment is folded.

As shown to advantage in Figures 3 and 4, the attachment 12 is secured to the rear waistband portion of a garment and disposed so that the hinge 22 will be arranged in registration with the waistband extension of the rear trousers crease. The front attachments 11 are connected with the front portions of the waistband in such arrangement that the section connecting hinges thereof will be arranged in registration with the waistline extension of the front creases. Due to the provision of the spaced apertures

18, the buttons 19, for the attachment of suspenders or the like, may be readily connected with the waistband portion of the garment and firmly connected thereto by extension through the stiffener attachments.

5 When the trousers 10, or other garment, equipped with the improved attachment is worn on the person, the complementary strips are readily bent arcuately to conform to the waistline curvature of the body so that the waist portion of the garment will be snugly fitted thereabout. When the garment is removed the pliable strips may be readily straightened by hand and each attachment is folded about the hinge connection so that the waistband portion of the garment is flattened to provide folds arranged in registration with or in continuance with the forward and rear creases therein, as shown to advantage in Figure 4. By this adjustment of the attachment and the garment, the wearer or attendant is enabled to quickly fold the trousers on the proper folding line so that the garment and the creases therein are preserved for an unusual length of time without the necessity of pressing the same.

It is to be understood that the form of my invention herein shown and described is 30 to be taken as a preferred example of the same, and that various changes as to the shape, size, and arrangement of parts may be resorted to without departing from the spirit of the invention or the scope of the 35 subjoined claim.

Having thus described my invention, I claim:

In combination with trousers, an attachment connected with the waistband portion 40 of said trousers comprising a pair of elongated sections of pliable material, and hinges connecting said sections together, the hinges being located in line and corresponding with the crease in the trousers, whereby 45 said trousers can be folded, after removal, along the crease therein.

In witness whereof I have hereunto set my hand.

NATHANIEL MORIN.
